UNITED STATES PATENT OFFICE

118,300

DESIGN FOR AN ASHTRAY OR SIMILAR ARTICLE

Charles E. Eckles, Washington, D. C.

Application June 9, 1939, Serial No. 85,435

Term of patent 7 years

To all whom it may concern:

Be it known that I, Charles E. Eckles, a citizen of the United States, residing in Washington, in the District of Columbia, have invented a new, original, and ornamental Design for an Ashtray or Similar Article, of which the following is a specification, reference being had to the accompanying drawing, forming a part thereof.

In said drawing:

Fig. 1 is a perspective view of an ash tray or similar article, embodying my new design.

Fig. 2 is a top plan view of the same.

Fig. 3 is a central vertical sectional view partly in elevation.

I claim:

The ornamental design for an ashtray or similar article, substantially as shown.

CHARLES E. ECKLES.
